(57) CLAIM

The ornamental design for a holder, as shown and described.

DESCRIPTION

FIG. 1 is a side, top, perspective view of the holder with elements thereof and thereon shown in phantom;

FIG. 2 is a bottom plan view thereof;

FIG. 3 is a top plan view thereof;

FIG. 4 is a right side elevational view, the left side elevational view being a mirror image thereof;

FIG. 5 is a front elevational view thereof; and,

FIG. 6 is a rear elevational view thereof.

The broken lines are for illustrative purposes only and form no part of the claimed design.
